T. Beaudry,

Saw-Mill.

No 92,777.

Patented Jul. 20. 1869.

Attest:
G. Talbot, Ambr. Law
Wm. N. Mygatt

Inventor: T. Beaudry

United States Patent Office.

TIMOTHY BEAUDRY, OF LEVIS, CANADA.

Letters Patent No. 92,777, dated July 20, 1869.

IMPROVEMENT IN SAW-MILLS.

The Schedule referred to in these Letters Patent and making part of the same.

To all whom it may concern:

Be it known that I, TIMOTHY BEAUDRY, of the town of Levis, Province of Quebec, and Dominion of Canada, have invented a new and improved Method of Hanging and Operating Gang-Saws for manufacturing lumber; and I do hereby declare that the following is a full and exact description thereof, reference being had to the accompanying drawings, and letters of reference marked thereon.

My invention relates to, and consists in a particular method of hanging and operating any desirable number of saws at one and the same time, without the use of the ordinary saw-gate; also, in a special arrangement of feeding-devices, whereby the logs are carried to, and the lumber from the saw, as will hereafter be more fully explained.

To enable others skilled in the art to make and use my invention, I will proceed to describe its construction and operation.

Figure 1 is a longitudinal section of a portion of the mill.

Figure 2 is a transverse section of the same.

Figure 3 is a plan view, and section of the log-carriage.

Figure 4 is a section of the hexagonal drum, by which the log-carriage is moved.

Figure 5 is a side view of the buckle, by which the saw is attached to the cross-head.

Figure 6 is a back view of fig. 5.

Figure 7 is a plan view of the gauges or saw-guides.

Figure 8 is a plan view of the upper slide and cross-head.

Figure 9 is a front view of the upper cross-head.

Figure 10 is a plan view of buckle *c*, showing a different method of attaching saws to the lower cross-head.

Figures 11, 12, and 13 are different views of the lower cross-head, with its slides.

Figure 14 is a side view of a strengthening-rod for the upper gauges.

A represents a portion of the frame of the mill.

d, a driving-shaft, revolving in suitable bearings, and carrying driving-pulley *f*, feed-pulley *g*, and crank-wheel *e*, to which the lower end of the bifurcated pitman *c* is attached.

The upper or forked end of the pitman *c* is secured by straps to the bar of the cross-head *i*, which reciprocates in slides *h*.

To the cross-head *i* the saws *a* are attached, by means of buckles *b*, figs. 5 and 6.

The lower gauge *g* is attached to the upper end of the slides *h*, and serves, in conjunction with the up-

per gauge *r*, to guide and steady the saws when in operation.

Attached to the upper portion of the frame *A*, are two perpendicular hanging-posts, to which the metallic slides *k* are secured.

In these slides are formed dovetailed grooves, in which the slides *j*, which are attached to the gauge *r*, operate.

In the rear of these slides is a horizontal shaft, *m*, carrying pinions, which operate upon a rack secured to the slides *j*.

Motion is given to the shaft *m* by means of the bevelled wheels *n o*, and hand-wheel *p*, for the purpose of raising or lowering the gauge *r*, to adapt it to the size of the log.

A cross-head, *l*, is attached to the upper end of the saws *a*, which reciprocates in the slides *j*.

To the upper end of these slides is secured a horizontal bar, *D*, to which the gauge-support *u*, fig. 14, is attached.

The log is fed to the saw, and the lumber carried from it, by means of an endless-chain carriage, moving upon longitudinal ways *B*.

Motion is given to this carriage by means of revolving hexagonal drums *x*, to which motion is imparted by any suitable gearing connected with the feed-pulley *g*.

For the purpose of holding the log in position while being operated upon by the saw, the sections *v* of the chain-carriage are hollowed, as shown in fig. 3.

These sections, in connection with the spiked pressure-rollers *t s*, hold the log firmly in position.

Having thus fully described my invention,

What I claim, and desire to secure by Letters Patent, is—

1. The method herein described of operating a series or gang of saws, without the use of gates or devices for straining them.

2. The chain-carriage *v*, in combination with the pressure-rollers *t* and *s*, when constructed and arranged to operate substantially as described, and for the purpose specified.

3. The buckle *b*, to which saws *a* are attached, in combination with the cross-head *i* and pitman *c*, when constructed to operate as described, and for the purpose specified.

4. The strengthening-rod *u*, attached to the bar *D*, in combination with the gauge *r*, when used as and for the purpose set forth.

Witnesses:

G. TALBOTT,
HENRY N. MYGATT.

T. BEAUDRY.
